CABLE VISE AND CUTTER FOR REMOVING ARMOR FROM CABLE

Filed March 7, 1952

UNITED STATES PATENT OFFICE

2,683,930

CABLE VISE AND CUTTER FOR REMOVING
ARMOR FROM CABLENial F. Walters, New Carlisle, Ohio, assignor to
the United States of America as represented by
the Secretary of the Air Force

Application March 7, 1952, Serial No. 275,449

2 Claims. (Cl. 30—91)

(Granted under Title 35, U. S. Code (1952),
sec. 266)

1

The invention described herein may be manufactured and used by or for the government for governmental purposes without payment to me of any royalty thereon.

This invention relates to a cable vise combined with a cutter for removing armor from cable. The action which is intended is a severing action, not a slitting action. The tool is especially adapted for use on the end of a bench and may be held down with one hand while being operated with the other.

Briefly stated, the device consists of two portions, a vise portion for holding and positioning the cable and a gauging and cutting portion for setting the depth of the cut and then for undergoing a manual rotation so as to traverse a cutting wheel completely around the cable under sufficient pressure to sever the unwanted portion of the armor from the rest of the stock. The severed portion of the armor must then be pulled from the strands of the cable by means of pliers or other tools.

One of the objects of the invention is to provide a device which will sever steel armor from cable without damaging the cable, notwithstanding the fact that the armor has been swaged into ridged contact with the cable. The kind of cable that is spoken of is used for parachute cables and the like as actuating wire and is not intended for electrical use. It lies within the purview of the invention however, to use the tool to remove insulation or lead jacket from electrical cable.

Another object of the invention is to provide a device in which the cutter can be accurately set to depth in a minimum of time and will preserve the depth setting for the entry of the cutter wheel into the armor through numerous operations of the cutting wheel.

Another object is to provide a device which will track the cutter wheel accurately so that the armor is severed cleanly and without a burr.

Referring now to the accompanying drawings, Fig. 1 is a perspective oblique view from above, the vise portion being at the left and the cutter portion being at the right.

Fig. 2 is a longitudinal section taken along the line 2—2 of Fig. 1.

Fig. 3 is a front elevation of the device from the cutter end, the internal operating parts being shown in dashed lines.

Fig. 4 is a cross-section taken on the line 4—4 of Fig. 3.

Fig. 5 is a cross-section taken on the line 5—5 of Fig. 3.

Fig. 6 is a partial vertical section taken on the line 6—6 of Fig. 3.

2

Referring again to Fig. 1, 10 indicates the vise portion and 11 the cutter portion of the device. The vise portion 10 is intended to be held manually, or otherwise mounted upon a work bench, the crosswise edge of which coincides with the line 12 which indicates the boundary between the cutter portion 11 and the vise portion 10. The cutter portion 11 is rotatable about the cable 13 which is shown in Fig. 1 both as projecting forward from the cutter portion 11 and rearward from the vise portion 10. The vise portion 10 comprises a longitudinally grooved lower block 14 and an upper block 15 through which a holding screw 16, having a large knurled head 17, projects. The two blocks are held together by screws as clearly indicated in Figure 1 of the drawings.

The cutter portion 11 has more height and less length than the vise portion and is provided with four mutually attached side plates 18, 19, 18a and 19a, an axle 20 mounted in the plates 19 and 19a which serves the purpose of retaining the cable longitudinally in an opening therethrough. The axle 20 is keyed to the plate 19 by means of a pair of keying screws 21. The cutter portion is characterized by the presence of a locking screw 22 which also has a knurled head 23 and which is set into a boss 24 on a top closure and guide 25.

Referring now to Fig. 2, it will be seen that the cable 13 is retained in the vise portion 10 by a semi-cylindrical shoe 26 which is vertically adjustable in a recess 27 by virtue of the fact that it is loosely retained upon the inner end holding screw 16 so that the recess 27 will hold it parallel with the cable 13 notwithstanding the rotation of the screw 16. The shoe 27 is adapted to cover about half of the cable circumference while acting as a vise jaw.

As will be seen from Fig. 2, the axle 20 extends from the front face of the cutting portion 11 well into the vise portion 10 and is there retained between blocks 14 and 15 by a flange 28. The axle 20, which is of round cross-section in that portion of its length which is retained between the blocks 14 and 15 is provided near its forward end with flats 29, 30 and 31. The flats 30 and 31 enable the axle 20 to fit respectively the front plate 19 of the cutter portion 11 and a rear plate 19a thereof. The flat 29, somewhat lower than flats 30 and 31, is dimensioned by means of a pair of shoulders 32 to receive a vertically slideable block 33 into the top of which the upper set screw 22 is rotatably retained with a round key 34 which is shown in Fig. 3 behind plate 19. The slideable block 33 at its lower end is bored trans-

versely for the accommodation of an arbor 35 upon which is mounted a cutting wheel 36 which may rotate on the arbor or be tightly pressed thereon so that the arbor rotates. A lower recess 37 in the axle 20 enables the cutting wheel 36 to reach the cable 13 which lies in a cylindrical cavity 38 which can be seen in full line in Fig. 5 and in dashed line in Fig. 3.

At the bottom of the axle 20 as shown in Fig. 2, there is a flat 39 which has shoulders 40 for the reception of the various plates including a bottom plate 41 which makes up that portion of the body of cutter portion 11 which is necessary to enclose the axle 20. Pins 42 lock the plate 41 to the plates 19 and 19a. Pins 43 lock the closure 25 to the same plates at the top of the cutter portion 11. The effect of this construction is to make the cutter portion body usable as a wrench to rotate the axle 20, which corresponds to a nut in that it has four flattened surfaces for the reception of a wrench, but differs from a nut in that it has considerable of a rotatable cylindrical bearing portion 20 enclosed within the blocks 14 and 15. The portion 11 is kept in good horizontal alignment by the cylindrical portion 20.

As will be seen in Figs. 4 and 6, a threaded opening 44 for the reception of a set screw 45 is provided in the bottom plate 41 at the side thereof. The set screw 45 makes contact with the lower end of the vertically slidable block 33 to furnish a stop to regulate the depth of cut which the cutting wheel 36 can make in the armor of the cable 13.

In operation, the screws 16 and 22 are first manually loosened, then the cable 13 is inserted into the vise portion 10 from the rear and is pushed forward through the cutter portion 11 until as much of the armor protrudes beyond the plate 19 as is judged suitable to be severed, taking into consideration the distance of the cutting wheel 36 from the front of the plate 19. Both screws 16 and 22 are then tightened, the cutting wheel 36 just resting on the top of the armor. The screw 22 is then advanced just enough to make the cutting wheel 36 cut through the armor, but not through the strands of the cable. The set screw 45 is then adjusted with a screw driver from below so as to make firm contact with the vertical slide contact 33. The left hand then retains the vise portion against rotation while the right hand rotates the cutter portion 11. The armor is now severed and the projecting piece is pulled forward with pliers to separate it from the cable strands. The device is now set for an infinite number of cuts if the dimensions of the cable and its armor remain the same. It makes no difference whether the rotation of the cutter portion is clockwise or counterclockwise, although clockwise rotation is more con-

venient for right handed persons. The cable is released from the device by loosening the screw 16. The foregoing operation may be accomplished more easily on the end of a bench so that the vise portion rests upon the bench and the cutter portion projects over the end, nevertheless the two can be used merely by holding it in the hands.

I claim as my invention:

1. A device for severing armor and the like circumferentially from cable, said device comprising a vise portion and a rotatable cutter portion, the vise portion comprising a lower grooved block, an upper grooved block and a screw-actuated holding device mounted in a recess above the groove of the lower block so as to be vertically adjustable therein, a flanged axle rotatably retained between said blocks, said axle forming a connection between the vise portion and the cutter portion, the latter comprising a vertically screw-adjustable block recessed at its lower end, an arbor mounted across the recess and a cutting wheel rotatable on said arbor, said cutting wheel projecting below the block into a recess in said axle so that said cutting wheel is able to contact cable laid longitudinally through said axle at the center of rotation thereof, a plurality of plates forming a case in which the block may be actuated, and through two of which said axle extends, a plurality of flats upon the axle in the cutter portion to give the axle a substantially quadrilateral cross section, top and bottom closures on said plates, an adjusting screw extending through the top closure into the vertically slidable block, said block and case constituting a wrench whereby the cutter portion may be rotated about the cable to enable the cutter portion to sever the armor.

2. A device according to claim 1 and in addition a vertically adjustable set screw in the lower closure of the case, said screw being adapted to be set to limit the downward travel of said vertically adjustable block and its associated cutter whereby to limit the depth of penetration to which the cutter can enter the cable when the block is forced downward under the urging of the adjusting screw.
